CLAIM

The ornamental design for a operation station machine for a biochemical analysis, as shown.

DESCRIPTION

FIG. 1 is a front, top and left side elevational perspective view of a operation station machine for a biochemical analysis showing our new design;

FIG. 2 is a front elevational view thereof;

FIG. 3 is a right side elevational view thereof;

FIG. 4 is a top plan elevational view thereof;

FIG. 5 is a bottom plan view thereof;

FIG. 6 is a left side elevational view thereof; and,

FIG. 7 is a rear elevational view thereof.

*FIG. 1**FIG. 2*FIG. 3

*FIG. 4**FIG. 5*FIG. 6

FIG. 7
